WILLIAM L. AINSWORTH AND AMOS D. WRIGHT, OF LOWELL,
MASSACHUSETTS.

Letters Patent No. 62,917, dated March 19, 1867.

IMPROVEMENT IN STOP-MOTION FOR FEEDING MECHANISM OF CARDING ENGINES.

The Schedule referred to in these Letters Patent and making part of the same.

TO ALL PERSONS TO WHOM THESE PRESENTS SHALL COME:

Be it known that we, WILLIAM L. AINSWORTH and AMOS D. WRIGHT, of Lowell, in the county of Middlesex, and State of Massachusetts, have made a new and useful Invention having reference to Carding Engines; and we do hereby declare the same to be fully described in the following specification, and represented in the accompanying drawings, of which—

Figure 1 is a top view.

Figure 2, a side elevation; and

Figure 3, a rear end elevation of the main portion of a carding engine, with our invention applied to its feeding and laying mechanisms.

The nature of our invention consists in a peculiar stop-motion, or stopping mechanism, and the combination of it and the feeding and laying mechanisms of the carding engine. The object of our invention is the stoppage of the feeding mechanism when the sliver of the laying mechanism may become broken. With the common carding engine, as provided with a laying mechanism applied to it or its feeding aprons, and being without any stop-motion or mechanism for automatically arresting the operations of the feeding mechanisms on breakage of the sliver while being delivered to the laying mechanism, it generally happens that the breakage is not discovered until sometime after its occurrence, in which case the unfilled space of the feeding aprons has to be supplied with the sliver laid in it by manuallabor. Our invention saves all this labor, and is advantageous in other respects.

In the drawings, A denotes the frame of the carding engine; B the main card cylinder; D the doffer; C the feeding cylinder, and E the upper of the two feed rollers. There goes around the lower feed roller, and a series of smaller rollers, $a a a a$, arranged obliquely with respect to it, a series of endless aprons or belts, $b b$ b . It is on these aprons or belts that the sliver, as it proceeds from the breaker, is laid by the laying mechanism, which may be thus described: The sliver is shown at S, as led through a carriage, e, and between two guide-rollers $d d$ fixed theron. This carriage is supported by or depends from a stationary and horizontal rod, e, fixed to a frame, f, which is erected over and across the series of belts $b b b$. The said frame carries two wheels, $f^1 g$, about which an endless belt, h , travels. A pin or stud, i, extending from the belt, goes through a slot, k, made vertically in and through the carriage e. The said endless belt is disposed directly in front of the carriage, and there is a bevelled gear, l, fixed on the shaft m of its wheel, g. Another bevel gear, n, fixed on a shaft, o, engages with the gear l. An endless belt, p, going around two pulleys $q r$ (one of which is fixed on the shaft o, and the other on the shaft s of the feeding cylinder C) serves to transmit rotary motion to the shaft o and its gear n, which in turn actuates the gear l. In this way the endless belt h obtains a continuous rotary motion. Such belt and its pin, i, will impart to the carriage e a reciprocating rectilinear motion, whereby the sliver will be laid first in one direction, and next in the opposite way, on the series of belts or aprons $b b b$.

The mechanism for operating the lower of the feed rollers, and, as a matter of course, the series of endless aprons, may be thus explained: A spur gear, t, fixed on the shaft or journal u of such roller, engages with a pinion, v, applied to the inner side of a bevelled gear, x, mounted on a spindle, w, projected from the side of the frame A. A long shaft, y, driven by a train of gears, $z a' b' c'$, which derives motion from a spur pinion, d¹, fixed on the shaft of the doffer D, carries a tubular shaft, e¹, and should be connected therewith by what is termed a "feather connection." This tubular shaft supports a bevel pinion, s¹, and slides freely on the shaft y, and is grooved transversely, as shown at d². A fork, e², enters the said groove, and is jointed to a shipper or lever, f², arranged on the side of the frame A in manner as represented in the drawings. A spring, g¹, applied to the frame A, and having its free end resting against or suitably applied to the fork, serves to move the fork so as to cause it to move the shaft e¹, with its bevel pinion s¹ on the shaft y, and in a manner to disengage the said frame from the bevel gear x. The shipper serves to enable a person to move the fork in the opposite direction in order to effect the engagement of the pinion s¹ with the said gear x. The shipper, when driven backward, springs into a notch, h¹, formed in a slotted plate, i¹, projected from the frame A. A small alarm bell, k¹, attached to the shipper by a spring, l¹, serves to give warning when breakage of the sliver and stoppage of the feeding mechanism take place.

The mechanism for forcing the shipper out of the notch h' may be thus explained: Within a standard, m' , is a slide, n' . A vertical section of the slide n' and the standard m' is shown in fig. 4, in which the slide is exhibited as having a pin, o' , extending back from it, and going through the standard. A spring, p' , serves to move the slide in one direction away from the shipper. A tri-armed lever, q' , is carried by the slider; the rear arm of such lever being heavier than and so as to overbalance the others, one of which extends horizontally, while the other is bent downward at an acute angle with the latter, as represented in the drawings. While the sliver may remain unbroken, it will, during the approach of its carriage toward the shipper, be carried into contact with the inclined arm of the tri-armed lever, and by being pressed against it will tilt the lever so as to prevent a projection, r' , of the carriage from being forced in contact with the smaller horizontal arm of the said lever. Should breakage of the sliver take place, there will be no tilting of the tri-armed lever during an approach of the carriage, but the projection r' will be carried into contact with the tri-armed lever, and will force the slider backward, in which case its pin o' , by pressure against the shipper, will discharge the latter from its notch, and thereby allow the spring g' to effect the disengagement of the bevel gears x and s' . On their disengagement the lower feed roller and its series of endless belts will cease to revolve, and thus there will be no further advance of the fibrous material laid on the belts. The attendant, on hearing the sound of the bell, which will be rung at the period of stoppage of the feeding mechanism, will know that breakage of the sliver has taken place, and he should at once proceed to piece up the sliver and set the feeding mechanism again in operation.

We make no claim to the sliver, feeding, and laying mechanisms of themselves, but what we do claim as our invention is as follows; that is to say—

We claim the peculiar stop-motion or mechanism for effecting the disengagement of the bevel gears s' and x ; and

We also claim the combination of such a stop-motion, or its equivalent, and the laying and feeding mechanisms, as described; and

We also claim the combination of the alarm apparatus, or its equivalent, with the stop-motion and the laying and feeding mechanisms applied to or making part of a carding engine, as described, the whole being substantially as and for operation in manner and for the object or purposes as hereinbefore explained.

WM. L. AINSWORTH,
A. D. WRIGHT.
